UNITED STATES PATENT OFFICE.

LESLIE H. GARLINGHOUSE, OF ASPINWALL, PENNSYLVANIA, ASSIGNOR TO BLOW-KNOX COMPANY, A CORPORATION OF NEW JERSEY.

PANEL.

1,426,374.

Specification of Letters Patent. Patented Aug. 22, 1922.

Application filed October 13, 1919. Serial No. 330,345.

To all whom it may concern:

Be it known that I, LESLIE HOLMES GARLINGHOUSE, a citizen of the United States, residing at Aspinwall, in the county of Allegheny and State of Pennsylvania, have invented certain new and useful Improvements in Panels, of which the following is a specification.

This invention relates to panels for use in constructing walls, floors, ceilings and the like for structures of plastic material, such for example as concrete.

Heretofore in panels of this character, difficulty has been encountered by virtue of the fact that the panels, during use, would not remain true and would warp and become otherwise distorted so that the edge portions of adjacent panels would only abut one another at intervals instead of throughout their length, as a result of which gaps would be left between the panels, causing among other things the formation of fins on the concrete. In addition it was difficult in the first instance to provide panels with straight edges, owing to the construction employed.

One of the primary objects of my invention is to overcome the foregoing difficulties by the provision of an improved panel of simple and rigid construction, which is easy to manufacture.

The foregoing together with such other objects as may hereinafter appear, or are incident to my invention, I obtain by means of a construction which I have illustrated in preferred form, in the accompanying drawings, wherein:

Figure 1 is a bottom plan view of two panels, as applied for the construction of a floor or ceiling; Figure 2 is a section taken on the line 2-2 of Figure 1; Figure 3 is a section taken on the line 3-3 of Figure 1; Figure 4 is a section corresponding to Figure 3, but illustrating a modification of my invention; and Figure 5 is a perspective of the end of a reinforcing member used in the panels.

Referring now to the construction shown

in Figures 1 to 3 inclusive, it will be seen that the panel is composed of a sheet metal plate 7, preferably rectangular in shape, with the edge portions at the sides thereof bent preferably at right angles and then inwardly, preferably parallel to the main portion of the plate. The side portions of the panels therefore are in channel like form which lends great rigidity to the panel longitudinally thereof. At the point where the edges of the plates 7 are bent to form the panel sides, I press a bead 8, extending longitudinally of the panel. It will be apparent that in the first instance, it is possible to make a panel having this beaded construction more true than a panel having a plain side with the bead omitted, and furthermore it will be seen that the bead will remain true in use for a longer period and is not nearly so liable to become warped and distorted.

A more perfect joint between adjacent panels is thus made possible, and in addition should any of the fresh material work through, between the beads, it will fall out because of the gap which is established between the bent over side portions below the beads. In addition, the beads lend additional rigidity to the panel longitudinally thereof and supplement the rigidity secured by the general channel-like formation of the sides.

In order to reinforce the panels and lend rigidity transversely thereof, I provide a plurality of reinforcing members 9, preferably in the form of channels, the ends of which are carried into the channel-like sides of the panel plate. The extreme end portions of the channels are cut away leaving fillets 10, shown more clearly in Figure 5, which are adapted to project into the beads. The channels 9 are secured to the channel plates in any preferred manner, as for example, by spot welding.

In the construction shown in Figure 4, a bead is provided at one side only of the panels, the construction in other respects being substantially the same.

The panels are secured to the mold structure in any manner, well understood in this art.

I claim:

- 5 A panel for concrete work comprising in combination a sheet metal plate having opposite edge portions thereof bent into channel-like form at least one of the web portions of the bent over edges having a lon-

gitudinally extending bead or rib member, 10 and a plurality of reinforcing members extending transversely of the panel, said reinforcing members having a fillet fitting into said bead.

In testimony whereof I have hereunto 15 signed my name.

LESLIE H. GARLINGHOUSE.
